PROCESS AND APPARATUS FOR PRODUC-
ING MINERAL WOOL

Lewis Willard Chantler, Charles Town, W. Va.,
assignor to The Standard Lime and Stone Com-
pany, Baltimore, Md., a corporation of Mary-
land

Application November 6, 1935, Serial No. 48,574

5 Claims. (Cl. 49—77.5)

This invention pertains to an improved apparatus for and method of blowing mineral wool. Such wool, as is well understood by those skilled in the art, is produced by directing a blast of fluid under pressure against a stream of molten scoria. The fluid medium may be steam or air and the scoria may have as its source various materials, such as rock of suitable character, slag, etc. Hereinafter, the material produced will be referred to as mineral wool, the term being employed in its broadest sense.

The present invention has for its object two main purposes, which in a sense and to a certain degree are interrelated, to wit, to thoroughly and evenly impregnate the wool and to provide means whereby the blast which blows the wool and likewise carries the impregnating material therewith may be changed in direction to ensure proper impingement with the scoria stream.

As a further object, the invention provides means whereby the direction of the blast is changed to maintain it in proper relation to the scoria stream, the conduits or means through or by which the treating material is supplied, also moves to the same extent and in the same direction, so that once the relative relation between the blast stream and the outlet or outlets for the treating material is fixed, they so remain under all adjustments of the blowing nozzle.

A simple embodiment of the apparatus whereby the method may be effected is disclosed in the annexed drawing, wherein:

Figure 1 is a sectional elevation of the lower portion of a cupola or furnace and the appurtenant features of my invention;

Fig. 2, a perspective view of the blowing nozzle mounting;

Fig. 3, a face view of the blowing nozzle of my invention; and

Fig. 4, a detail sectional view of the nozzle and a portion of the cupola.

In the drawing, 10 denotes the cupola having a notch 11 in the lower forward edge above which there is left a suitable opening closed by any suitable means as 12, to afford access to the interior of the cupola. The notch is commonly closed initially by a mass of fire clay 13 or the like, and an opening made therethrough by a rod producing an opening of the desired and requisite size from which a stream of scoria 14 flows.

In actual practice, the stream does not always flow downwardly in the same path, this due primarily to the possible slight hardening thereof at one or another portion of the opening through

which it flows. Change in consistency of the scoria also tends to vary the path of flow.

The blowing nozzle is denoted by 15 and is shown as a hollow member having a series of small openings 16 in its forward face, said openings in communication with the interior of the nozzle and receiving air or steam under pressure from a branch pipe 17 connected to an adjustable main supply pipe hereinafter set forth in detail.

The openings are preferably arranged in the form of a V with the lower elements thereof arranged in substantially circular series instead of in true convergence as at the bottom of an ordinary V.

An opening 18 is likewise formed in the face of the nozzle or blowing head, said opening being surrounded by and equally spaced from the circularly arranged openings 16 at the bottom of the series. Said opening is in direct communication with a conduit 19 which in turn is connected to a pipe 21 leading to a source of so-called treating material, such as starch, sodium silicate or any of the well known materials commonly employed in the art to impart coherence to the blown wool fibers. No pressure need be applied upon the material passing through pipe 21 as such material is sucked out and carried forward by the air or steam jets passing from the openings 16 located adjacent the outer end of opening 18 and carried into the scoria by such jets.

Overlying the nozzle 15 is a relatively small pipe 22, the outer end whereof is practically flush with the flat forward face of nozzle 15, the opposite end being connected with an oil reservoir (not shown) which effects a gravity feed of oil which ultimately trickles or flows down over the nozzle face until it is picked up and carried forward by the minute streams of fluid under pressure passing from the openings 16.

As above indicated, means is provided for adjusting the blowing nozzle 15 with reference to the scoria stream and to that end the mechanism best shown in Figs. 1 and 2, or its equivalent, is employed to ensure the blast contacting and, in a sense, surrounding the scoria stream 14. Said stream in practice has a tendency to flow from one or the other side of the opening, this seemingly because of the chilling of the scoria and unless the blast is properly related thereto, the wool produced will not be uniform and excessive "bead" formation takes place.

Pipe 17 which at its forward end carries the nozzles 16 freely rests adjacent said end in a saddle 23 adjustable as to height to the under

face whereof is attached a nut 24. A threaded shaft 25 passes through and engages the nut 24, the shaft at one end being supported by a bracket 26 secured to the supporting framework 27 of the cupola. At the other end, the shaft passes through a suitable bearing 28 detachably attached to a hanger 29 extending downwardly from the framework 27. A crank 31 is secured to the shaft in order that it may be rotated to cause the traveller nut 24 to be moved in one or the other direction or longitudinally of the shaft.

As the nut is moved, saddle 23 is traversed along shaft 25 and as a consequence pipe 17 is swung laterally to bring nozzle 15 to the requisite position with reference to the scoria stream which for best results should fall within the V arrangement of the openings 16.

To permit the nozzle 15 to be swung laterally, the rear end of pipe 17 is connected to a cross pipe 32, one end whereof is closed as by a cap 33, while the other is connected by a pipe 34 with a source of air or steam under pressure, a flexible connection (not shown) being employed to admit of free adjustment of the pipe 32 and its attached parts.

A pair of bracket-like members 35 and 36 secured to the framework 27 underlie pipe 32, the lower horizontally disposed elements whereof support the pipe and related elements while still allowing free movement of the pipe and said elements to vary the position of the nozzle.

Means is provided for shifting the pipe 32 and, consequently, the pipe 17 and nozzle 15 forwardly and backwardly so as to advance and recede the nozzle from the scoria stream. To this end, a threaded shaft 38 is supported by suitable brackets 39 and 41, the latter having a bearing element 42 attached thereto and in which the shaft 38 moves. Adjacent its rear end, the shaft 38 has mounted thereon a shipper plate or arm 43, the upper bifurcated end whereof engages the pipe 32 and as the shaft 38 is rotated, as by movement of a crank 44 attached to the shaft, the member 43 is moved forwardly or backwardly and, as a consequence, the pipe 32 with the parts thereto attached likewise moves forward and backward, advancing or receding the nozzle 15, as above indicated.

By mounting the pipe 17 in the saddle 23, said pipe may be readily shifted and what is more, the parts may be readily disassembled if need be merely by lifting the pipe from the saddle and disengaging the pipe 32 from the shipper 43.

The bracket 41, which is secured to the framework 27 extends downwardly to such position as to bring the cranks 31 and 44 relatively close to each other, whereby the attendant of the blowing apparatus may readily rotate one or the other of the shafts 25 or 38 without changing his position. This, of course, is not essential, but is a matter of convenience.

Normally, the mineral wool, or fibers thereof, which is indicated generally in Figs. 1 and 4 by the reference numeral 45, is designed to pass through an opening 46 formed in the adjacent wall or face of a so-called blowing or settling chamber (not shown).

In operation, oil passing from the pipe 22 wends its way downwardly over the rearwardly inclined face of the member 18 and is picked up and carried forward by the jets, primarily those in the upper portion of the series. This oil, as is well known in the art, (see the Patent to Fay No. 1,242,537 of October 9, 1917), tends to oil the

fibers and in a sense to soften the same when the fibers are considered as a mass. The binding material which is drawn outwardly by the suction action of the jets which surround the mouth of the pipe 18, is carried forwardly into the scoria by said jets and ultimately comes with the wool which is being blown or has been blown and has been oiled. There is no primary admixing of the oil with the stiffening material, nor any solution of one in the other.

As will be appreciated, the apparatus is at once simple and yet withal has been found effective in actual operation. As stated at the outset, the binding material may take various forms well known in the art, such as bituminous, resinous substances, silica of soda, glue, dextrine, etc. The character of the binding material will, to a certain extent, depend upon the use to which the material is to be put.

Seemingly, by using the fine openings as 16, there is formed a series of jets which tend to break up and diffuse the oil as well as the binding material and to protect the same from being burned by the scoria, inasmuch as the materials introduced are in effect surrounded by the steam at least for a period sufficiently long to prevent them from being destroyed to such an extent at least as to inhibit their functional action upon the finished mineral wool. By separating the points of introduction of the oil and the stiffening agent or material, either one or the other may be changed or completely shut off and, as a consequence, the final product may be varied according to demand.

By mounting the nozzle 15 in the manner above set forth, it may be said to have a universal adjustment. It may be moved through any line or arc which is desirable or necessary to bring the jets into proper relation to the scoria stream, with a view of obtaining the best results.

What is claimed is:

1. That method of blowing mineral wool, which consists in projecting a stream of fluid under pressure in a series of jets against a stream of molten material, permitting oil to pass downwardly to said jets at the zone of their inception to be picked up and carried forwardly thereby, and presenting a liquid stiffening material to the effective suction action of some of the jets at least, whereby the oil and the stiffening material will be carried forwardly in an atomized condition into the scoria immediately the jets contact the scoria.

2. That method of blowing mineral wool, which consists in projecting a stream of fluid under pressure in a series of fine jets against a stream of molten material, and carrying forwardly by certain of said jets into such material a treating material, said jets picking up and subdividing said treating material as it is carried forwardly.

3. In combination with a cupola, a blowing nozzle standing adjacent an opening formed in said cupola from which a stream of molten material may flow; a pipe extending rearwardly from said nozzle; a support for the rear end of said pipe, said support comprising brackets and a transversely extending pipe connected to the rear end of the first named pipe, said transversely extending pipe resting upon and movable over said brackets; a shipper embracing said transversely extending pipe; a screw threaded shaft for adjusting said shipper and thereby moving the pipes forwardly and backwardly with reference to the stream aforesaid; a saddle standing beneath the forward portion of the first named pipe and

forming a support therefor; and a threaded shaft passing through a threaded portion of said saddle whereby by rotation of said last named shaft the nozzle may be swung laterally in either direction.

5. A structure as set forth in claim 3, wherein means is provided for raising and lowering the saddle with reference to the shaft.

10. 5. In combination with a cupola, a blowing nozzle standing adjacent an opening formed therein from which a stream of molten material may flow; a pipe extending rearwardly from said nozzle and through which fluid under pressure is

conveyed to the nozzle; a support for the rear portion of said pipe; means for adjusting said pipe upon the support to move the nozzle bodily in an axial direction toward and from the stream of molten material; and means for shifting the nozzle laterally with reference to said stream, said means comprising a saddle in which the nozzle supporting pipe rests and is free to move longitudinally together with means for moving the saddle laterally.
